[57] CLAIM

The ornamental design for a combined sign support and
clip therefor, substantially as shown.

DESCRIPTION

FIG. 1 is a front perspective view of a combined sign
support and clip therefor showing my new design;
FIG. 2 is a top plan view thereof;
FIG. 3 is a side elevational view taken from the left of
FIG. 1, the side opposite being a mirror image thereof;
FIG. 4 is a front elevational view thereof.

FIG.1

FIG.2
